United States Patent Office.

ROBERT E. TOLAR AND WILLIAM D. ORR, OF NEWNAN, GEORGIA.

Letters Patent No. 106,236, dated August 9, 1870.

IMPROVED AUTOMATIC TABLE-FAN OR BRUSH.

The Schedule referred to in these Letters Patent and making part of the same.

To all whom it may concern:

Be it known that we, ROBERT E. TOLAR and WILLIAM D. ORR, both of Newnan, in the county of Coneta and State of Georgia, have invented a new and useful Improvement in Automatic Table-Fan or Brush; and we do hereby declare that the following is a full, clear, and exact description of the same, reference being had to the accompanying drawing forming part of this specification.

Our invention relates to a useful device for operating one or more fans or brushes, for the purpose of creating a current of air and driving away insects, and consists in the fan or brush with its several parts connected with suitable driving mechanism, as will be hereinafter more fully described.

In order to enable others skilled in the art to make and use our invention, we will now proceed to describe its construction and operation.

Figure 1 shows the interior works or driving mechanism of our automatic fan or brush.

The mechanism or clock-work is arranged or enclosed in a frame which is made of two plates, A A, connected by four or more studs, *a a*, secured together similar to a clock-frame.

Between these plates is a spindle, B, with a gear-wheel, *b*, pawl *c*, and ratchet-wheel *b'*.

The driving-wheel *b* gears into the pinion *d* upon the shaft *B'*, and to this shaft is attached a gear-wheel, *d'*, which also gears into the pinion *f* formed upon the shaft *C*, which has a gear-wheel, *e*, similar to those before mentioned.

Directly back of the shaft *C* is a spindle, having a pinion, *e'*, which gears into the wheel *e*, and carries the fly-wheel *E*.

The motion of the fly-wheel is stopped by slide *g*, having a projecting pin, *h*, which, by moving the button, is brought into contact with said wheel.

This stop is intended to be fastened to one side of the box or receptacle which holds the gearing of our automatic fan, and is shown in the drawing by the perpendicular section of the box at *F*.

Fastened to the spindle *B* is a coiled spring, *G*, the other end being fastened to a pin, or any convenient way, underneath the plate *A'*.

Upon the shaft *C* is a crank, *i*, and to this a connecting-rod or arm, *j*, said arm being rigidly attached to the bent part of crank *k* of the shaft *H*, one end of which passes through the standard *I*.

K is a rod, upon the lower end of which is fastened a sleeve, *M*, having a socket which fits down upon the upper end of crank-shaft *H*, and is kept in place by thumb-screw *l*.

There can be one or more of these sleeves with rods *K* fastened one upon the other by the means described; for instance, when it is desired to have the fans or brushes further from the table, upon the end of rod *K* is fitted an adjustable sleeve, made fast at any desired point upon the rod by a thumb-screw in passing through the sleeve and bearing upon the rod *K*. Upon each end of the sleeve *L* are holes to receive the handles of the fans or brushes, which are placed at opposite direction and at right angles to the shaft or rod *K*.

If desired, fans of ordinary construction may be used, the handles of said fans being made adjustable by the thumb-screws.

We have shown in the drawing thin strips of ribbon or cloth, fastened to the handles *p* by being passed through slits made therein, and held firmly by small pins or screws.

The operation of this machine will be easily understood.

The spring *G* being wound up, motion will be communicated to the train of wheels above described, the revolution of which will impart motion to the shaft *C* and gearing-wheel *e*, which, through the crank *i*, and connecting-rod *j*, bent rod or crank *K*, an oscillating motion to the brushes or fans upon the sleeve *L* will be imparted.

Having fully described our invention,

What we desire to secure by Letters Patent is—

The combination of the crank *i*, connecting-rod *j*, bent rod or crank *K*, running through the standard *I*, rod *K*, provided with sleeve *M* and screw *z*, adjustable sleeve *L*, set-screws *n n* and *m*, arms *P* with brushes or fans, slide *g* and stop *h*, and fly-wheel *E*, constructed and arranged to operate in connection with the driving mechanism hereinbefore described, for the purpose specified.

R. E. TOLAR.
W. D. ORR.
